(57) **CLAIM**

The ornamental design for a shelf system, as shown and described.

DESCRIPTION

FIG. 1 is a second perspective view of the door for a dialysis recharger cabinet;

FIG. 2 is a front view of the second perspective thereof;

FIG. 3 is a rear view of the second perspective thereof;

FIG. 4 is a left side view of the second perspective view thereof;

FIG. 5 is a right side view of the second perspective view thereof;

FIG. 6 is a top view of the second perspective view thereof;

FIG. 7 is a bottom view of the second perspective view thereof;

FIG. 8 is a cross-sectional view taken along lines 8-8 from FIG. 2 of the lower portion of the door thereof; and,

FIG. 9 is a cross-sectional view taken along lines 9-9 from FIG. 2 of the higher portion of the door thereof.

The elements shown in broken lines are for illustrative purposes only and form no part of the claimed design.
